WILLIAM B. COFFIN AND JOSEPH R. COFFIN, OF BLISS, NEBRASKA; SAID
WILLIAM B. COFFIN ASSIGNOR TO SUSAN F. COFFIN, OF SAME PLACE.

WELL-SINKING MACHINE.

SPECIFICATION forming part of Letters Patent No. 395,034, dated December 25, 1888.

Application filed November 19, 1887. Serial No. 255,563. (No model.)

To all whom it may concern:

Be it known that we, WILLIAM B. COFFIN and JOSEPH R. COFFIN, both of Bliss, in the county of Wheeler and State of Nebraska, have invented a new and Improved Well-Sinking Machine, of which the following is a full, clear, and exact description.

The object of the invention is to so construct the tube used in drilling the well by the assistance of hydraulic pressure that it is made to form a permanent part of the well after water is reached.

The invention consists in the construction and arrangement of certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is an enlarged front elevation of the drilling-tool and the valve-pipe. Fig. 2 is a sectional elevation of the valve-pipe on the line *x x* of Fig. 1. Fig. 3 is a sectional plan view of the same on the line *y y* of Fig. 2.

The lower tube, *F'*, of the well-tubing *F* carries a collar, *F*², in which is secured a valve-pipe, *L*, carrying on its lower end a collar, *L'*, on which is secured the tool-pipe *N*, carrying the drilling-tool *O* on its lower end. The drilling-tool *O* is a flat piece of steel, which extends into a slot formed in the middle of the pipe *N*, and is provided at its upper end with a shank, *O'*, fitting into the pipe *N* above said slot. A bolt, *O*², fastens the drilling-tool *O* to the lower end of the pipe *N*. The lower end of the pipe *N* is slightly spread, as illustrated in Fig. 1, so that the water passing down the pipe *N* is spread over the lower surface of the drilling-tool *O* on each side, so as to wash off all adhesive matter from the said drilling-tool. The drilling-tool *O* is slightly curved on its cutting-edges, and the said drilling-tool is provided in its lower part with the two cutting-edges 1 and 2, forming a point at their intersection, and then extending upward, diverging from each other, and then continuing into the vertical and parallel cutting-edges 3 and 4, from which extend the inward cutting-

edges 5 and 6, which are joined to the edges of the shank *O'*.

In the valve-pipe *L* are formed two rows of apertures, *L*², placed close together, said rows being placed diametrically opposite each other, as illustrated in Figs. 2 and 3. Each row of apertures *L*² is covered on the inside by a valve, *P*, secured at its upper end by rivets *P'* to the valve-tube *L*. In the lower end of each valve-pipe *P* is formed a vertical slot, *P*², into which extends a rivet, *Q*, secured to the lower end of the valve-pipe *L*. The slot *P*² in each of the valves *P* permits an upward motion of the lower end and inward bending of the said valve whenever the water from the vein presses strongly through the apertures *L*² against the said valve, or when the water is drawn inward from the vein when operating the well-pump in the usual manner. The water can then pass on account of the bending of the said valve on the inside of the valve-pipe *L* into the latter and up through the tubing *F* to the outside of the valve.

The valve-pipe *L* is preferably covered by a wire-gauze, *R*, so as to prevent heavy substances from passing into and through the apertures *L*², but the only object of the valves *P* is to cause the water in the drilling operation to be forced through the end of the pipe; but these valves do not interfere with the free inflow of water after the vein has been reached.

In the upper end of the tool-pipe *N* is inserted a hollow wooden plug, *S*, carrying on its lower end a valve, *T*. This plug and valve are specially adapted for deep wells in which quicksand is present, and they serve to prevent an upward movement of the quicksand into the pipes *L* and *F*. The plug *S* is made of wood, so that it can be destroyed when it becomes necessary to locate the valve-pipe *L* in sand or fine gravel, for the reason that in some veins of water the sand contained in it is so fine that it obstructs a free flow of water through the gauze *R*, and hence the plug and its valve *T* must be removed, which is done by an auger secured to piping and let down the tubing until the auger strikes the wooden plug. The piping is then turned so that the auger bores out the plug. Sufficient sand is

now removed from the bottom of the well below the tool O by a sand-pump or other means, to form a cavity sufficiently large to enable the fine substances which obstruct the free flow of water through the gauze R to settle down into the said cavity. A solid wooden plug is then driven into the tool-pipe N, which is thus closed up.

The drilling-tool O usually descends at a speed of about two inches to one revolution of turning, and the vertical cutting-edges 3 and 4 serve to leave the wall of the well-hole smooth and regular. The upper cutting-edges, 5 and 6, provide against resistance when necessary to raise the piping any given distance subsequent to a completion of the well. The valves P yield inwardly to the pressure of the water in the vein in order to supply the cylinder of the pump. The slots P² allow a slight upward motion and insure a free flow of the water through the screen or gauze R and the perforations L².

It will be understood that when the two valves meet at their extreme inner centers when pressed inward they do not obstruct the free flow of water into the piping above. In sinking wells by hydraulic force it often occurs that the operator misjudges the most desirable locality to establish the perforated valve-pipe L. After the operation ceases, the pump is started and the mistake is apparent. Then it is best to remove the pump and proceed the same as before the valve-pipe L was located. If the pipe at the first trial is supposed to be too deep, the downward flow of the water shuts the valves P, causing the upward flow to hold back the yielding strata, and the pipe can then be raised or lowered at will.

Having thus fully described our invention, we claim as new and desire to secure by Letters Patent—

1. The combination, in a well-boring machine, of a perforated tube having inward-opening valves with an open-ended tool-carrying tube connected to its lower end and a downward-opening valve below the first-named valves, whereby sand or other solid matter is prevented from rising through the tool-tube and closing said inward-opening valves, and the said valves will close and the lower one open when hydraulic pressure is applied in drilling, substantially as set forth.

2. In a well-boring machine, the combination, with the tube having a vertical series of

apertures, of a flexible strip secured to the inside of the tube, covering said apertures, and having a sliding connection with the tube, substantially as set forth.

3. In a well-boring machine, the combination, with the tube having a longitudinal series of apertures, of a flexible strip secured to the inside of the pipe over said apertures, one end of the strip being slotted and having a headed guiding-pin or rivet passing therethrough, substantially as set forth.

4. The combination, with the open-ended tool-carrying tube and the perforated tube connected to the upper end thereof and provided with an inward-opening valve for said perforations, of an intermediate short wooden tube closed at its lower end against upward pressure by a downward-opening valve, whereby the wooden section may be destroyed when its valve is no longer necessary to the successful operation of the said inward-opening valve, substantially as set forth.

5. In a well-sinking machine, the combination, with a valve-pipe secured to the well-tubing and provided with rows of apertures and a wire screen or gauze covering the outside of said valve-pipe, of valves held on the inside of said valve-pipe and operating over said rows of apertures, a tool-pipe held on the lower end of the said downward-opening valve-pipe, and a valve held in the said tool-pipe, substantially as described.

6. In a well-sinking machine, the combination of a main pipe, a perforated tube connected to the lower end of said pipe, a drilling-tool connected to the lower end of said perforated pipe, and valves located within said perforated tube covering the perforations and opening inward, substantially as shown and described.

7. In a well-sinking machine, the combination of a main tube, a drilling-tool with a hollow upward extension, a perforated tube located between said main pipe and drilling-tool, having inward-opening valves over the perforations, and a valve opening downward, located between the said perforated tube and the drilling-point, substantially as shown and described.
